UNITED STATES PATENT OFFICE.

PHARES M. MISHLER, OF HAGERSTOWN, MARYLAND.

DESIGN FOR A FENCE-STAY.

SPECIFICATION forming part of Design No. 27,012, dated May 4, 1897.

Application filed March 30, 1897. Serial No. 629,986. Term of patent 14 years.

To all whom it may concern:

Be it known that I, PHARES M. MISHLER, a citizen of the United States, residing at Hagerstown, in the county of Washington and State of Maryland, have invented and produced a new and original Design for Wire-Fence Stays; and I do declare the following to be a full, clear, and exact description of the same, reference being had to the accompanying drawing, forming a part thereof.

The figure of the drawing represents a side view of a fence-stay, showing my design, this one figure being necessary only to fully illustrate my design.

This design of a fence-stay is more particularly intended to be used with horizontal wires of a wire fence which consists of several strands or cables.

The leading feature of my design consists of a series of elongated openings C, formed by twisting two wires together, the inner faces

of the sides of the openings C being parallel to one another and terminating at the upper and lower points a a.

A represents the fence-stay, which in general contour is corrugated, presenting a twisted stem the upper portion of which terminates in a ring or circular opening B, while the lower portion presents a cut - off end. These elongated openings present slots and are at intervals with the intermediate, presenting a double twist of wire strands.

What I claim is—

The design for fence-stays herein shown and described.

In testimony whereof I affix my signature in presence of two witnesses.

PHARES M. MISHLER.
